UNITED STATES PATENT OFFICE.

CHRISTIAN BUNK AND HERMANN F. KUECHLER, OF KENOSHA, WISCONSIN.

VESSEL-SALVAGING APPARATUS.

1,405,895.

Specification of Letters Patent.

Patented Feb. 7, 1922.

Application filed April 14, 1921. Serial No. 461,236.

To all whom it may concern:

Be it known that we, CHRISTIAN BUNK and HERMANN F. KUECHLER, a citizen of German Republic and a citizen of the United States, respectively, and residents of Kenosha, in the county of Kenosha and State of Wisconsin, have invented certain new and useful Improvements in Vessel-Salvaging Apparatus; and we do hereby declare that the following is a full, clear, and exact description thereof.

The invention relates to improvements in vessel salvaging apparatus, and more particularly to a type of the same adapted to 15 be permanently carried on a vessel as a part of its regular or standard equipment.

The principal object of the invention is to provide for an apparatus of the character mentioned, and one of an extremely 20 simplified construction capable of being installed on new vessels during their building, or on old vessels, without seriously affecting the present design of such vessels, and without utilizing an appreciable amount 25 of the otherwise valuable space within the hull portions thereof.

Another object of the invention is to provide an apparatus of the type specified, and one which is automatically rendered available 30 for use in connection with the raising operation of the sunken vessel simultaneously with the sinking of the latter.

A further object of the invention is to provide an apparatus of the class set forth, 35 and one embodying a tell-tale means for indicating the exact position of a sunken vessel so that the same may be readily located for the salvaging operation after having been sunk for a long period of time.

With the foregoing and other objects in view, the invention resides in the certain novel and useful construction and arrangement of parts as will be hereinafter more fully described, set forth in the appended 45 claim, and illustrated in the accompanying drawings, in which:—

Figure 1 is a sectional view through a body of water in which a vessel having the invention installed thereon has been sunk, 50 the vessel being shown in side elevation with the tell-tales of the salvaging apparatus floating on the surface of the water, and

Figure 2 is a transverse sectional view through the hull of the vessel and through 55 one of the wells thereof in which is located one of the units of the salvaging apparatus.

Referring to the drawing, the numeral 10 indicates generally the hull portion of a vessel, and 11 one of the wells disposed vertically within the same, two or more of such wells being provided depending upon the length of the particular hull in which the apparatus is to be installed. As shown in Figure 1, however, two of these wells 11 are ordinarily used, and are disposed on 60 the longitudinal center of the hull 10, one spaced inwardly of the bow end thereof and the other inwardly of the stern end of the same.

Each well 11 comprises a metal casing 12, 70 of a suitable height to have the lower end thereof secured to the bottom wall of the hull 10, or otherwise passed through the wall and secured to a metal sheathing or reinforcement 13 secured on the under surface of the latter, and the upper end of the same opening through the upper deck of the vessel. The upper open end of the casing 12 is formed to provide an outwardly extending or right angular flange 14 adapted 80 to closely overlie the adjacent edges of the deck flooring, and an inwardly extending or right angular flange 15 upon which is to be seated a buoy or float *a*, the latter being held in position thereon, against all lateral 85 displacement, by means of a vertically extending flange 16, all of the flanges 14, 15 and 16 being extended entirely around the walls, or wall, as the case may be, of the casing. These casings 12 may be either 90 square, oblong or circular in horizontal cross-section, and the floats *a* and *b* correspondingly shaped to seat on the flanges 15 thereof in a manner to normally close the open ends of the same.

Each buoy, or float *a* and *b* is provided with an eye member or bolt 17 secured centrally in the under face thereof for the attaching thereto the free end of a rope or cable 18 which is normally coiled upon the 100 vertically disposed cone shaped member 19, the base of which is supported upon an angle member 20 secured to the intermediate portion of the casing 12.

The cable 18 is held to the float and is 105 coiled upon the cone 19 in such a manner that its free end passes downward through the small end of the cone and having secured thereto an eye terminal 21 in which is permanently secured, but loosely, the free 110 end link of a hoisting chain 22 which is coiled upon itself within the lower portion

of the casing 12, the lower end link of the same being loosely secured, but permanently, in an eye bolt 24 which is passed through the bottom wall of the hull 10 and headed 5 on its opposite ends so as to be securely incorporated in the latter.

With two, or more, of the wells 11 installed on a vessel as indicated herein, and with the salvaging units assembled therein 10 and otherwise arranged in accordance with with the invention, immediately upon the sinking of the vessel from any cause whatever, the buoys or floats *a* and *b* will float free from the open ends of the casings 12 15 and the cable will uncoil from the cone according to the depth to which the vessel sinks, and, should the cables be insufficient for the purpose of allowing the floats to remain on the surface, the chains 22 will be 20 withdrawn from the lower portion of the casings, it being understood that the total length of the cables and chains will be sufficient for at least the average depth of the water on which the vessel will travel on a 25 particular or regular voyage, so that the buoys or floats will remain on the surface as tell-tales for the location of the same for salvaging operations. After a sunken vessel has been located, as indicated by the presence 30 of the floats, the exact position of the same is to be determined by the relative position of the latter, and the salvaging crew will then be able to proceed with the necessary work of raising the vessel to the surface, such as will be readily accomplished, 35 and otherwise greatly facilitated, by hauling the cables upward until the attached ends of the chains 22 are above the level of the water, when suitable power means can 40 be attached thereto for the winding up of the same and the subsequent hoisting of the vessel.

From the foregoing, it will be readily apparent that the invention provides for a 45 very efficient means for the accomplishment of the desired purposes of the same; that

under ordinary circumstances the raising or salvaging of a vessel is assured by reason of the hoisting chains being permanently secured to the hull of the same; that the salvaging operation is greatly simplified by reason of the important part of the necessary apparatus which is permanently installed on vessels as a standard part of their equipment or as an addition to such equipment; that the exact location and position of a sunken vessel will be readily ascertained by the provision of buoys or floats connected toward the opposite ends of the hull portion thereof; and that the expenditure in 55 time, money and lives will be reduced to a minimum in raising simply a vessel on which the apparatus is installed as compared with the present and known methods of salvaging operations. 60

It is well understood that the construction and arrangement of the parts of the invention as described herein is subject to unlimited variations, changes, modifications, and substitution of equivalents, without the same being construed as being a departure from the scope of the claim appended hereto. 65

Having thus fully described our invention, what is claimed is:

In combination with a vessel, of a casing formed therein, a buoy closing said casing at its upper end, a vertical disposed conical sleeve within the casing, a cord wound upon the exterior of said sleeve and attached at 80 one end to said buoy, the other end of the cord passing through the sleeve and adapted to be attached to a lifting cable coiled within the casing and the latter being attached to the ship. 85

In testimony that we claim the foregoing we have hereunto set our hands at Milwaukee, in the county of Milwaukee and State of Wisconsin.

CHRISTIAN BUNK.
HERMANN F. KUECHLER.
